June 4, 1929.

M. S. JOYNER

1,716,173

SCALP PROTECTOR

Original Filed May 16, 1928

INVENTOR.
Marjorie S. Joyner
BY
E. C. Broome & Co.,
Her ATTORNEYS.

UNITED STATES PATENT OFFICE.

MARJORIE STEWART JOYNER, OF CHICAGO, ILLINOIS, ASSIGNOR TO THE MADAME C. J. WALKER MANUFACTURING COMPANY, OF INDIANAPOLIS, INDIANA, A CORPORATION OF INDIANA.

SCALP PROTECTOR.

Original application filed May 16, 1928, Serial No. 278,174. Divided and this application filed November 26, 1928. Serial No. 321,942.

This invention relates to a scalp protector.

The object of the invention is the construction of a simple and efficient protector for the scalp, used by hairdressers in the permanent waving process.

Another object of the invention is the construction of a novel and efficient protector that is placed against the head of a person with a bunch of hair extending therethrough, whereby the curling iron can be placed close to the head without any discomfort to the patron.

This application is a divisional case, growing out of my prior application Ser. No. 278,174, filed May 16, 1928, "permanent waving machine" and which case will become a patent on November 27, 1928, No. 1,693,515.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a perspective view of my device, showing the same placed around approximately one square inch of hair on the patron's head.

Figure 2 is an enlarged perspective view of the device, and the beginning of wrapping of the hair on the iron.

Figure 3 is a folded perspective view of the device.

Referring to the drawings by numerals, 1 designates my scalp protector, which is preferably formed from a blank sheet of material and comprises a body 2 that is provided at one edge with an incut 3 in which the bunch of hair 4 (Fig. 1) is placed; extending from one end of body 2 is an elongated tongue 5.

In Figure 1, the scalp protector is shown placed against the patron's head, with the bunch of hair 4 extending beyond or above the protector, and in Figure 2, is shown the first position of wrapping the hair on the curling iron 6, then the scalp protector can be wrapped around the curling iron with the tongue 5 lapping over the body a considerable distance, making a very secure binding for holding the hair efficiently in place upon the curling iron.

Additional illustration of this device will be found in my Patent No. 1,693,515, hereinbefore mentioned.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. A scalp protector, comprising a body provided with a hair-receiving incut and with a projecting wrapping tongue.

2. A scalp protector formed from a blank sheet and comprising an elongated body and tongue, said tongue projecting from one end of the body and being reduced in size compared to the body, and said body provided in one edge with an inwardly extending hair-receiving incut, substantially as shown and described.

3. A scalp protector formed from a single sheet or blank and comprising a body provided with an outwardly extending tongue and with a hair-receiving incut extending into the body at right angles to the line of extension of said tongue.

In testimony whereof I hereunto affix my signature.

MARJORIE STEWART JOYNER.